UNITED STATES PATENT OFFICE.

JOHN SHUTTLEWORTH, OF FRANKFORD, PENNSYLVANIA.

POWER-LOOM.

Specification of Letters Patent No. 7,387, dated May 21, 1850.

To all whom it may concern:

Be it known that I, JOHN SHUTTLEWORTH, of the borough of Frankford, in the county of Philadelphia and State of Pennsylvania, 5 have invented certain new and useful Improvements in Looms; and I do hereby declare that the following is a full, clear, and exact description of the nature, construction, and operation of the same, reference being 10 had to the drawings hereunto annexed and making part of this specification, in which drawings only those portions of the loom are shown which are effected by my improvements.

15 One part of my invention consists in combining the advantages incident to rising and falling heddles with those peculiar to the "cylindrical jacquard," that is to say, the formation of the shed in the warp is effected 20 by a descending as well as an ascending motion of the heddles, and thus is avoided the unequal tension, and consequent liability of the warp to stretch and snap which takes place in all cylindrical jacquards known to 25 me. Aside from this defect however the compactness, precision, stability, and other radical advantages of the cylindrical jacquard are too well known among weavers to require specific recital here.

30 Another part of my invention consists in arrangements of structure in the cylindrical jacquard to facilitate adjustment to the pattern, so as to enable the weaver to accomplish in a few minutes what is usually the 35 work of hours.

Another part of my invention consists in the arrangement of mechanism by which is effected the intermittent and gradual rotation of the cylinder.

40 Another part of my invention consists in improvements on the mechanism for operating the picker staffs.

In the annexed drawings, Figure 1, is a front elevation of the loom. Fig. 2, is a 45 rear elevation thereof. Fig. 3, is a top view. Fig. 4, is a transverse sectional elevation on the dotted line x, x , of Fig. 1. Fig. 5, is a transverse section of the drum or cylinder.

The same letters on the above figures refer 50 to corresponding parts.

(a) is the external framework of the machine.

(b) is the driving shaft, bearing an eccentric worm (c) and a pinion (d). From this 55 worm and pinion are derived all the move-

ments of the heddle frames and pickers in the manner hereinafter described.

Two rails (e) extend horizontally from front to back of the machine, at an equal distance from the center, being bolted at 60 their extremities to the frame (a). Resting upon and bolted to these rails are two standards (f) which have each of them a vertical slot (g) forming guides for the journal boxes (h) of the jacquard cylinder 65 (i, j, k). To these standards and rails are also affixed the journal bearings (l) of the various rods and levers used to operate the heddles.

(m) are the guides of the heddle frames 70 (n, o, p), which are of the usual form.

(q) are the heddle rods or "needles" by which the jacquard cylinder is enabled to operate on the heddles.

The jacquard cylinder consists of the following parts to wit; two heads (i) which carry the gudgeons or journal pins. Extending from one to the other of these heads and somewhat within their circumference is a hollow drum or cylinder (j) pierced with 80 the usual holes for the reception of the heddle rods. This drum is cased with segmental plates (k) which when placed around the drum, make the exterior of the middle portion flush with the heads. The segments also are pierced with holes corresponding to those on the drum and are attached to the drum by screws or otherwise.

The regulation of the patterns is effected 85 by plugs or stoppers (t) somewhat similar in form to common rivets. These stoppers are inserted between the shell and the drum, so as to intercept such holes as represent the particular meshes in the pattern which are

to be occupied by the warp, the rivets are 90 prevented by their heads from slipping through the holes, and by their shanks (which penetrate slightly into the shell) from any deviation. One gudgeon of this 95 drum carries at its extremity a crown wheel 100 (u) having the same number of cogs as there are longitudinal tiers of holes in the drum. Meshing into this wheel is a scroll cam (v w) whose rim or verge is for the most part (v) of its circumference in a 105 plane square with its shaft, but is separated at one part into two portions (w) which lap past each other with a shear or draft equal to the pitch of the cogs on the crown wheel. The driving shaft is so connected 110

on the one hand with the jacquard, and on the other with the picker staff that the shed is opened by the heddles and the shuttle projected by the picker at given periods of 5 each revolution of the shaft. The straight portion of the cam serves to hold the wheel and jacquard at rest in the intervals between the successive flights of the shuttle, and it also serves to guide the scroll between the cogs. It is during this interval 10 also that the jacquard drum is caused to ascend and the rail or heddle bearer (*r*) supporting the heddle frames to descend by the following arrangement of apparatus, to 15 wit:—

At each end of the standards (*f*) are hung two levers (*x y*) the upper pair of these (*x*) are journaled at one end to the frame and near their mid length to slide blocks (*s*) 20 appended to the heddle bearer (*r*) which blocks slide within the vertical guides (*g*). The other pair of levers (*y*) are journaled to the standards near their third-length and the journal boxes (*h*) of the drum at their 25 ends, so that a depression of the free ends of the levers (*x* and *y*) must cause the drum and heddle bearer *r* to approach each other and of course, a contrary motion of the levers must cause the drum and heddle 30 bearer to recede from one another. The free ends of these levers are connected together by links or shackles (*z*) and an arm (*a'*) extending from one set to the other is connected by a pitman (*b'*) to a crank (*c'*) 35 on a shaft (*d'*) which carries a pinion (*e'*) actuated by a spur wheel (*f'*) on the tappet shaft (*g'*) set in motion by the pinion (*d*) on the driving shaft (*b*). Now as the diameter of each pinion (*d*) and (*e*) is precisely equal to half that of the wheel (*f'*) 40 it follows that the crank shaft (*d'*) and the driving shaft (*b*) must each revolve in equal times, and consequently that the drum (*i*) and heddle bearer (*r*) will be made to 45 approach and recede simultaneously and equally, the levers (*x y*) being arranged for that object by means of the adjustable centers (*h' i'*). The levers (*x, y*) are not hung directly to the frame (*f*) but are connected 50 to it by short links or shackles *J, K*, in order that they may accommodate themselves to the vertical motion of the drum and bearer. Thus by making the heddle bearer to descend at the same time that the cylinder 55 ascends, is avoided the unequal tension of the warp, before alluded to, as a defect, to which the ordinary cylinder jacquard is liable, and the adaptation of the peculiar form of eccentric worm in the manner de-

scribed dispenses with a great deal of complexity of parts and irregularity of action inseparable from the old rack and pinion movement.

The jacquard may be moved one two or more tiers between every pick by the substitution of either a smaller crown wheel, or a cam of greater pitch.

The wheel (*f'*) on the tappet shaft (*g'*) having exactly double the diameter of the driving pinion, rotates but once during two revolutions of the latter, but as the tappet rollers (*T*) are placed on opposite sides of the shaft, a picker, (each alternately) is set in motion at every revolution of the pinion.

Immediately below the tappet rollers *T* 75 are treadles (*l'*) whose upper edge swells into a protuberance (*l''*) at first nearly concentric with the tappet, but curving rapidly upward, so as to receive from the tappets and impart to the arms a rapidly accelerated motion, which in the picker-staff is still farther increased by the shortness of the arms (*m'*) on the picker-staves (*n'*) within an eye in which arms the free extremities of the treadle (*l'*) play.

The picker staves are retracted by springs (*o'*).

The tappets are adjustable in concentric slots *B* in their bearings in order that the flight of the shuttle may be duly timed and adapted to the opening of the shed.

Having thus fully described the nature, construction, and operation of my invention, what I claim therein as new and desire to secure by Letters Patent is—

1. The imparting to the heddle bearer (*r*) a motion simultaneous with, and in opposite direction to, the vertical one of the cylindrical jacquard (*i j k*) by an arrangement of supplementary levers (*x*) and their appendages as herein described, or by mechanism substantially equivalent, the scroll cam or split pulley *v, w*, being so arranged as to act alternately as a lock and guide, and as a cam.

2. The arrangement and combination, substantially as described and represented, of a segmental shell (*k*) and stoppers (*t*) for the ready adjustment of the jacquard to the pattern.

In testimony whereof I have hereunto signed my name before two subscribing witnesses.

JOHN SHUTTLEWORTH.
